UNITED STATES PATENT OFFICE.

CHARLES M. MUSGROVE, OF PITTSFIELD, MASSACHUSETTS.

STOPPING MECHANISM FOR KNITTING-MACHINES.

SPECIFICATION forming part of Letters Patent No. 449,910, dated April 7, 1891.

Application filed July 9, 1890. Serial No. 358,198. (No model.)

To all whom it may concern:

Be it known that I, CHARLES M. MUSGROVE, a citizen of the United States, residing at Pittsfield, in the county of Berkshire and State of Massachusetts, have invented new and useful Improvements in Stopping Mechanism for Knitting-Machines, of which the following is a specification.

This invention relates to stop-motions for circular-knitting machines, the object of the invention being to provide a mechanism for insuring the stoppage of the knitting-machine on the presence of or entrance between the series of circularly-arranged needles and the stitch-wheel of lumpy or bunched places in the yarn.

The mechanism of this invention is designed for application upon the knitting-machine without the material alteration of any of the usual contrivances thereon, and it is intended to operate in conjunction with the stop-motion mechanism which is at present commonly employed for insuring the stoppage of the knitting-machine immediately or shortly after the production of the knit fabric having bunched or lumpy places therein; and the invention consists in the construction and combination of parts, all substantially as hereinafter more fully described, and set forth in the claims.

In the accompanying drawings the present improvements are illustrated, Figure 1 being a perspective view of the front portion of a circular-knitting machine, showing a common form of a stop-motion device applied thereon which is capable of being actuated by the presence of lumps or bunches in the knit fabric, and also showing the stop-motion devices of the present invention which are actuated directly on the entrance to the knitting-needles of yarn having a bunch or lump therein. Fig. 2 is a view in perspective, on an enlarged scale, of portions of the new and improved stop-motion mechanism.

In the drawings, A represents the rotating cylinder, around which the series of needles (indicated by a) are arranged.

B represents the power-shipping lever, the arm b of which engages with the driving-belt, all so that when the lever is swung in the proper direction the driving-belt will be trans-

ferred from the fixed to the loose pulley, as most common in this class of knitting-machines.

On the arm c of the power-shipping lever 55 there is a fixed extension c', which extends over the table C of the knitting-machine.

D represents a form of stop-motion which has been heretofore employed, which insures the stoppage of the machine shortly after a 60 lump or bunch is knitted into the fabric. This mechanism comprises a supporting-standard 10, in a vertical socket of which a vertical shaft 12 is supported for a partial rotary reciprocating or rocking motion, there 65 being on said shaft a fixed radial arm 13, having its inner extremity 14 formed with fingers, which are adapted to bear with a yielding pressure upon the lower courses of the knit fabric, and, as well known, on the passage under the said fingers of a portion of the already knit fabric which has a bunched place knit thereinto or in which there may be a hole, as produced by imperfect knitting, the arm 13 will be swung and the shaft 12 75 rocked. The said shaft has a cam-formed projection 15 thereon, which forces the latch-lever 9 out of its latch-socket 16. The said lever 9 is then free to swing and permit the action of the spring-constrained shipper-lever 80 B to secure the stoppage of the machine.

The devices of the present improved stop-motion mechanism will be now fully described.

g represents the usual stitch or loop forming wheel carried on the inner end of the 85 horizontal spindle f, which is mounted radially with relation to the needle-cylinder upon the barrel or tubular bracket h, said barrel being carried on a standard i rising from the table. The spindle has an endwise motion 90 through the barrel, it being normally held in its innermost disposition by a spring within the barrel suitably applied to the spindle. There is formed on or attached to the outer end of the barrel h a yoke or support j. 95

k represents a trigger pivotally supported on the said yoke j and adapted by gravity to be maintained in its normal position of engagement with a latch or pawl, to be soon particularly described. The said trigger k has 100 a suitable portion or member, as the one l, with which a flange m on the axially-movable

spindle f has an engagement. As shown, the latch-engaging part n of the trigger works within a vertical groove o in the said yoke j , which groove is intersected at or about at right angles thereto by another groove p in the said yoke.

q represents the latch above mentioned, and which is pivotally mounted at q' upon the said yoke j for a swinging movement in a vertical plane which is angular to the plane of swing of the said trigger. Said latch (see Fig. 2) has its upper extremity of a hook form, which enters the said groove or slot p . A comparatively stiff spring r is applied with relation to said latch to insure the swinging thereof in the direction indicated by the arrows in Fig. 2.

s represents a shipper-rod which is suitably supported for a movement toward and from the vertical shaft 12, said shipper-rod being guided as to a portion thereof in a suitable way provided therefor in said yoke j , and in proximity to the said latch q said rod s has a shoulder t , and there is another shoulder u on said shipper-rod s , which is in proximity to the end of a radial arm v , which is secured upon or has an engagement with the said rocking shaft 12.

The operation of the machine will now be described, it being assumed that the shipper-lever B is in its position for placing the belt on the driving-pulley and that the latch-lever 9 is so held by its engagement in the socket 16 that the shipper-lever B will be held against swinging. The latch q is placed in the position (shown in Fig. 2) of engagement with the trigger, and the thread is guided in the usual way through the eyes in the guide w behind the stitch-wheel g and between the latter and the needles. The existence of abnormal conditions either as to the form of the thread or as to its free passage to the knitting-needle will insure an outward pressure on the stitch-wheel and an outward movement thereof and of its carrying-spindle f . For instance, should a knot or lump or bunch in or of the thread pass behind the stitch-wheel the same will insure, on the attempted forcing of such bunched portion of thread by the stitch-wheel wings between the needles, the outward yielding of the wheel and its supporting-spindle; or, again, should the thread for any reason be restrained from freely passing through the eye or eyes in the thread-guide, as the usual one, as shown at w , the tension then imparted to the thread will outwardly force the stitch-wheel. The motion being imparted outwardly to the stitch-wheel and its supporting-spindle through the flange m , swings the trigger k out of engagement with the latch q , which latter is then free to be swung by its spring, the top of the latch, by its engagement with the shoulder t on the shipper-rod s , moving said rod endwise, and through the consequent swinging of the arm or extension v the rock-shaft 12 is caused partially to rotate, and the cam pro-

jection 15 thereon throws the lever 9 out of latch, and, as plain, the shipper-lever B is then free to be spring-swung to insure the stoppage of the knitting-machine.

As is well known, it is common in circular-knitting machines simultaneously to knit four courses in the production of tubular knit fabric, four stitch-wheels being provided at proper intervals around the needle-cylinder, there being provided suitable guides for the thread coming from separate bobbins respectively provided for each stitch-wheel, and I therefore usually provide trigger and latch devices, substantially as described, in the operative relation to each of the stitch-wheel spindles set forth, and I provide one shipper-rod s , which is circular or of arc form, and which is in common with all of the latch and trigger devices of the series, said shipper-rod s being provided in advance of each latch q with the shoulder-piece t , and thus it will be seen that should such conditions of the thread be present at or in relation to any stitch-wheel mechanism of the series as would insure imperfect knitting the movement of the shipper-rod s will be insured for effecting the stoppage of the machine.

It will be noted, Fig. 2, that the extremity n of the trigger is beveled, whereby the contact thereagainst at its front side by the latch-hook will insure the slight swinging movement of the trigger which is necessary to permit of the movement of the latch to be engaged by the trigger. Therefore, the parts having been actuated for the stoppage of the machine, the temporary engagement of the trigger and latch may be readily restored by the moving of the shipper-rod s in the proper direction, so that a shoulder t thereof will force the latch which has been disengaged back into its position of engagement with the trigger.

What I claim as my invention is—

1. The combination, with the power-shipper device of a knitting-machine and a latch for maintaining the same in its position for insuring the running of the machine, and the stitch-wheel and its yielding carrying-support, of a trigger having an engagement with said stitch-wheel support, a spring-actuated latch adapted to be restrained by said trigger, and movable connections between said latch and the latch for restraining said power-shipper device, for the purpose set forth.

2. The combination, with the power-shipper device of a knitting-machine and a latch for maintaining the same in its position for insuring the running of the machine, of the stitch-wheel and its spindle-support which is adapted for a yielding action and is provided with an extension or flange m , a yoke or support mounted in relation to said spindle-support having the intersecting slots o and p , a trigger k , pivoted on said yoke and having a member in engagement with said flange m and another member located within said slot o , a spring-constrained latch pivotally mount-

ed on said yoke and having a portion which enters said slot *p* for engagement with said trigger, and movable connections between said latch and the latch which restrains said power-shipping device, for the purpose set forth.

3. The combination, with the power-ship-
ping device of a knitting-machine and a latch
for maintaining the same in its position for
insuring the running of the machine, of a
series of stitch-wheels with yielding carrying-
supports respectively provided therefor, trig-
gers mounted for engagement, respectively,
with stitch-wheel supports, spring-constrained
latches adapted to be confined by said trig-
gers, a shipper-rod ranging in proximity to
said several latches and having abutments to
be engaged thereby, and movable connections
between said shipper-rod and the latch which

restrain said power-shipping device, for the 20
purpose set forth.

4. The combination, with a power-shipping
device of a knitting-machine and a latch for
maintaining same in its position for insuring
the running of the machine, and a restrain- 25
ing-seat for said latch, and a rock-shaft 12,
having a cam projection thereon for forcing
said latch from its seat, of the stitch-wheel
and its carrying-support, a trigger having an
engagement with said support, a spring-actu- 30
ated latch adapted to be held by said trigger,
and a medium of connection between said
latch and said rock - shaft, substantially as
and for the purpose described.

CHARLES M. MUSGROVE.
